UNITED STATES PATENT OFFICE.

JOHN W. MACKNIGHT, OF NEW YORK, N. Y.

METHOD OF LAYING ARTIFICIAL PAVEMENTS.

SPECIFICATION forming part of Letters Patent No. 393,568, dated November 27, 1888.

Application filed September 3, 1888. Serial No. 234,447. (No model.)

To all whom it may concern:

Be it known that I, JOHN W. MACKNIGHT, of New York city, New York, have invented a new and Improved Method of Hardening the 5 Surface of an Artificial Pavement, of which the following is a specification.

This invention relates to an improved method of hardening the surface of an artificial pavement. Its object is more particularly to form 10 a hard corrugated surface or finish upon the uppermost layer.

The invention consists in the various features of improvement more fully pointed out in the claims.

15 In the accompanying drawings, Figure 1 is a perspective view, partly in section, of an artificial pavement constructed according to my improved method. Fig. 2 is an enlarged vertical transverse section through part of the 2 upper layer of the same.

In laying my improved pavement I first form a base of rocks, *a*, with an upper layer, *b*, of coal-ashes, these two layers constituting the foundation. Upon the foundation there is 25 placed the third layer, *c*, composed of one part of ashes, one part of sand, and of a suitable quantity of cement. Upon the layer *c* there is placed the top layer, *d*, composed of crushed trap-rock and hydraulic cement. The layer *d* slopes 30 from house-line to curb-line to constitute a water-shed, and both layers, *c* *d*, are turned downward at the curb to form the curbstone. While the layer *d* is still in a plastic condition I corrugate it by a suitable roller from house-line to curb line, and preferably also down the 35 curb to the lower edge of the same. Thus water-ways will be formed, which, as the pavement has a fall, will conduct the water directly down into the gutter. As the ribs between the corrugations are comparatively thin,

it is of importance that they should be thoroughly hardened while setting. To this effect I pour a wash over the surface of the pavement directly after the ribs are formed. This wash will flow along the grooves down into the 45 gutter, and while flowing will come into contact with both sides of the ribs. Thus the ribs are for a time inclosed between two streams of the wash. As hydraulic cement sets most quickly and perfectly when air is excluded 50 and when under water, the ribs will quickly and thoroughly harden. By extending the grooves down to the gutter-line the wash will not spread all over the curb, but will flow down in even streams to uniformly harden the 55 entire curb.

The wash I prefer to use consists of ten parts of water, two parts of ammonia, two parts of alum, and one part of an iron solution. After the ribs have been subjected to the wash 60 for about thirty minutes the pavement is completed.

What I claim is—

1. The method of hardening an artificial pavement, which consists in forming grooves 65 in the surface of the top layer while still plastic from house-line to curb and pouring a hardening-wash into the grooves, substantially as specified.
2. The method of hardening an artificial 70 pavement, which consists in forming grooves in the top layer while still plastic and pouring a wash consisting of water, ammonia, alum, and iron into the grooves, substantially as specified.

JOHN W. MACKNIGHT.
